UNITED STATES PATENT OFFICE.

JOSEPH M. DAPRON, OF ST. LOUIS, MISSOURI, ASSIGNOR TO NATIONAL PNEUMATIC COMPANY, OF NEW YORK, N. Y., A CORPORATION OF WEST VIRGINIA.

SAFETY CAR-CONTROL MECHANISM.

Application filed January 26, 1925. Serial No. 4,918.

My invention relates to improvements in safety car control mechanism, having for its object to provide passenger cars with pneumatic door-operating means, the car being 5 provided with a turnstile, making provision for the passenger, in exit from the car, to operate the door engine by means of the turnstile.

In connection therewith, my invention 10 provides for door opening from the exterior of the car by a street fare-taker; and for the locking and unlocking of the turnstile by the motorman, to control the exit of passengers through the turnstile.

From all of which should be understood 15 that my invention relates to passenger cars of the one-man-operated type, in which the motorman has control of the means of exit through a single rear-end door, and that 20 door may be opened or closed by a street fare-taker at congested points. In cars of the type in question, passengers usually enter by a front-end door, adjacent to the motorman, who collects the fares as the passengers enter; and the rear door is used for 25 exit only except when it is opened for the admission of passengers at points of traffic congestion, by a fare-taker stationed in the street outside the car, who collects fares from 30 the passengers as they enter the car.

The instant invention is particularly intended for use upon cars equipped with the air brake and safety car control mechanism of my United States Letters Patent No. 35 1,515,841 issued November 18, 1924.

Drawings.

Figure 1 is a plan view of a car equipped with the mechanism of my invention.

Fig. 2 is a vertical view, partly in section, 40 of the turnstile mechanism employed in my invention.

Fig. 3 is a top plan view of the ratchet locking and release mechanism employed in 45 connection with said turnstile.

Fig. 4 is a transverse mid-sectional view of the locking cylinder employed in connection with the turnstile mechanism.

Fig. 5 is a diagrammatic view of the piping 50 and air system employed in connection with my invention.

Description.

The mechanism of my invention is particularly intended for use upon one-man-

operated cars; or upon two-man-operated cars where it is desired to dispense with the rear end man or conductor at times. It also has provision for operation by an outside or street-fare-taker.

The diagram of Fig. 1 indicates at 6 the turnstile-locking control valve to be operated by the motorman, when the car is in use as a one-man car. I have there illustrated (Fig. 1) a car having a rear door 7 which 60 may be opened and closed by a street-fare-taker stationed outside the car and operating a valve 8. When the door is not operated by such street-fare-taker, the mechanism of my present invention, to be hereinafter 65 described in detail, will come into play to permit the ingress and egress of passengers through the door 7.

The turnstile A consists of the head 12 having the radial arms 13, normally mounted 70 in a horizontal plane; but the head 12 is seated in the tubular standard 14 as shown in Fig. 2, when the arms 13 are in horizontal position, and the head may be drawn upwardly out of its seat in the upright 14, and 75 dropped into the approximately vertical position indicated by dotted lines in Fig. 2. This is effected by reason of the connection between the head 12 and turnstile shaft 15, said shaft 15 having at its top the vertical 80 loop 16, extending into the cylindrical cavity 17 of the head 12, the head 12 being slidably secured to said loop 16 by means of the pin 18. The shaft 15 rotates freely in the tubular standard 14, said standard 14 being 85 mounted in the hollow bearing-block 20.

Within said bearing block 20, the shaft 15 is provided with a box collar 21, from which collar 21 the arm 22 extends radially, having at its outer end the tubular chamber 23, in the lower open mouth of which tubular chamber 23 a ball bearing 24 is yieldingly mounted by means of the coiled spring 25'; said ball 24 operating upon the upper surface of the circular plate 25, which plate 25 is provided with the dwell or depression 26 wherein said ball 24 will rest, as shown in Fig. 2, when the turnstile A is in its locked position. The said turnstile A is controlled by means of the ratchet wheel 27 which in 100 turn is mounted upon the tubular shaft 15 at a point conveniently below the car-floor 28.

When the car is in motion the ratchet wheel 27 is locked by means of the plunger 110

29 being seated in one of the holes 30 which extend vertically through the ratchet wheel 27 as shown in Figs. 2 and 3; the plunger 29 is mounted on the lever 31, fulcrumed at 32 and actuated by the operation of the locking cylinder 33, which contains the piston 34 and rod 35 as shown in Fig. 4, the coiled-spring 36, held in place by the cylinder head 37 serving to normally hold the piston 34 seated as shown in Fig. 4. The operation of the motorman's valve 6 admits compressed air to the cylinder 33 through the pipe 38, actuating the piston 34 and lever 31 to unseat the plunger 29 from engagement with the ratchet-wheel 27. The same movement of the motorman's valve 6 admits air through the pipe 41 to the cylinder 39 to disengage the pawl 40 from the ratchet-wheel 27 (the cylinder 39 containing a piston 34, rod 35 and coiled spring 36 as in the case of the cylinder 33 and as shown in Fig. 4 in detail).

26 The base of the turnstile shaft 15 has a socket 42 engaging with the valve-stem 43 of the valve 44 which valve 44 is described and shown in my United States Letters Patent No. 1,515,841 issued November 18, 1924, and forms no part of my present invention. It will suffice to describe said valve 30 44 as having pipe connections to the main compressed-air reservoir 49 and door-engine 50 (all as described and shown in my former Letters Patent), so arranged that the operation of the valve 44 by the turnstile A, 35 caused by the passage of a passenger through said turnstile A will serve to open the door 7, said door 7 being closed when desired by the motorman, actuating the valve 44 through the control-valve 6 and the pipe connections shown in Fig. 5. The control-valve 6 is fully illustrated in my Letters Patent No. 1,515,841 of November 18, 1924, and forms no part of my present invention.

40 The pawl 40 is so disposed as to permit the reverse movement of the turnstile A caused by passengers entering the car through the door 7, when that door has been opened by the operation of the control-valve 8 actuating the door-engine 50. Suitable connections between valve 8 and cylinder 33 release the plunger 29 concurrently with the release of pawl 40.

45 The piston 34 with its enclosed elements, constitutes a locking mechanism which is formed as shown in Fig. 4, the outer annular face 50 having a conoidal shoulder 51 fitting the beveled valve-seat 52 and terminating in the small circular constricted face 53. The air emitted from the pipe 38 first impinges upon the constricted face 53 to unseat the piston 34 from the valve-seat 52, permitting the expansion of the air-volume and its impact upon the entire piston-head comprising the constricted face 53,

the shoulder 51 and outer annular face 50. 65 The rod 35 thus receives an initial drive of relatively small force which is abruptly intensified as the shoulder 51 leaves the valve-seat 52.

As will be seen in Fig. 3, the ratchet wheel 27 would be freely rotatable in anti-clockwise direction at all times if it were not locked by the plunger 29. Conversely, to permit the clockwise rotation of the ratchet-wheel 27 the pawl 40 and plunger 29 must both be disengaged from the ratchet-wheel 27. That disengagement occurs when the door 7 has been opened by the operation (by the street-fare-taker) of the valve 8 (see Fig. 1), or (by the motorman) of the valve 6. Both of these operations are inaccessible to the passengers.

Mode of operation.

The car upon which my mechanism is 85 installed being brought to a stop by the motorman, by the operation of the valve 6 the ratchet 27 and lock 29 are released through the action of the cylinders 33 and 39 disengaging the plunger 29 and pawl 40. The passengers then effect their exit through the turnstile arms 13, the rotation of the turnstile actuating the stud 43 operating the control valve 44 to actuate the door engine 50 to open door 7. If the entrance of passengers only is to be effected the street-fare-taker by the operation of the valve 8 operates door engine 50 and opens the door 7, and at the same time unseats the plunger 29 from its locking position in the ratchet-wheel 27, permitting the passengers to pass the turnstile A. The exit of passengers, by revolving the turnstile arms 13 and the stud 43 actuates the engine 50 to open the door 7 which may be closed, and the turnstile A locked, by the motorman through the use of the valve 6.

The locking-means for the turnstile A is not accessible to passengers, and is controlled 110 by the motorman through the means above described.

The shifting of the turnstile head 12 into the vertical position indicated by dotted lines in Fig. 2 is intended to economize 115 space when the door 7 is not being used either for entrance or exit purposes.

I claim—

1. A safety car control mechanism comprising, in a passenger car, a door; means 120 operable from without the car to open and close said door; and a turnstile mounted within the car and arranged to be actuated by the exit of passengers to open said door.

2. A safety car control mechanism comprising, in a passenger car, a door; means operable from without the car to open and close said door; and a turnstile mounted 125 within the car and arranged to be actuated

by the exit of passengers to open said door with a locking-means for said turnstile not accessible to passengers.

3. In a safety car control mechanism, a door, a turnstile, and fluid operated means for moving the door comprising a valve actuated by the turnstile.

4. In a safety car control mechanism, a

door, a turnstile, and fluid operated means for moving the door comprising a valve actuated by the turnstile and a fluid operated control for the turnstile comprising a remote, manually operated valve.

In testimony whereof I have hereunto affixed my signature.

JOSEPH M. DAPRON.
